PLASTER CAST CUTTING MACHINE

Martin Merkur, New York, N. Y., assignor of one-third to Arnold Neustadter, New York, N. Y.

Application April 15, 1950, Serial No. 156,117

4 Claims. (Cl. 30—144)

1

This invention relates to a plaster cast cutting machine.

The machine which is herein described and claimed has been designed principally for use in cutting plaster casts of the type employed in bone fractures and similar conditions. The machine is not limited, however, to plaster cast work, and it may be utilized in many operations in many fields and industries which have no relation whatsoever to surgery. For example, the present machine is well adapted to cut laminated material, such as laminated paper, wood or plastics and it is equally well adapted to cut sheet material such as paper, rubber or cloth, piled layer upon layer. And similarly, the machine may also be utilized for the purpose of cutting relatively solid materials such as plaster of Paris, wood or plastics. For the purposes of the present application, however, the invention will be described solely in terms of its use in surgery, but this will be done solely for purposes of convenience and illustration and not by way of limitation.

The manner in which plaster casts are now removed from the patient, is crude and cruel in the extreme. Hammer and chisel are used to chip and break the cast and enormous shears are also employed in an effort to cut the material of which the cast is made. There is not always sufficient room between the cast and the patient's skin to accommodate the shears, especially where the tissues are swollen. In consequence considerable injury and pain result from efforts to force the shears underneath the plaster cast. An indication of how difficult it is at the present time to remove a sizable cast from a patient may be found in the fact that it may take half a day for two experienced men to hack and chop and chisel and cut the plaster cast before the patient may be said to be completely freed therefrom. It is difficult, if not impossible, to keep the patient in a state of anaesthesia during this entire period of time and hence the patient must suffer the agonizing pain which unavoidably accompanies present methods of removing plaster casts. The present invention was born of just such experiences in American service hospitals during the last war.

Plaster casts are not normally placed directly against the skin of the patient. Instead a layer or layers of absorbent cotton and/or gauze are interposed between the patient's body and the plaster cast. The plaster adheres to, and in part permeates, the cotton or gauze on which it is placed and so it is insufficient, when removing the plaster cast, to provide plaster chopping or

2

cutting means: it is equally necessary to provide means for cutting the cotton or gauze. Nor is it enough that means be provided for cutting or chopping the plaster and for cutting the cotton or gauze: it is at least equally important to provide means for adequately guiding and controlling cutting means and to prevent the cutting means from injuring the patient's body.

It is accordingly the principal object of this invention to provide a plaster cast cutter which:

- a. Cuts both the plaster and the cotton or gauze which lies below the plaster,
- b. is extremely easy to guide and control, and
- c. includes means for preventing injury to the patient's body.

More specifically, the plaster cast cutter constituting the present invention, provides means for sawing the plaster and for cutting or shearing the cotton or gauze. Still more specifically, the present invention provides a pair of reciprocating saw blades, each of which provides its own sawing action, both blades cooperating with each other to provide a cutting or shearing action between them. The two blades are mounted

25 side by side, in abutment with each other. The cutting action of one of the saws is directed downwardly and the cutting action of the other saw is directed upwardly. Since the two saws move in opposite directions at the same time, 30 one of the saws will tend to pull the entire cutting mechanism away from the patient's body and the other saw will tend to pull the entire cutting mechanism toward the patient's body. These two pulling forces will neutralize each 35 other and no unbalanced forces will be set up which the operator of the device will be unable to control. Hence, it will be found extremely easy to manage and guide the present device.

It has above been stated that each saw provides its own cutting or sawing action and that the two saws provide a cutting or shearing action between them. That each saw will provide its own sawing action, is clear. The shearing action takes place by reason of the inter-action 45 between the cutting teeth of the two saws. These teeth are not offset from each other as is the case with conventional saw blades instead they are flush with at least one side wall of the blade proper and when the two blades are held side by side in abutment with each other, the cutting teeth of each blade will coat with the cutting teeth of the other blade to provide a shearing action and more particularly, a plurality of shearing actions, determined by the number of teeth 50 in the two blades and by the number of times

each tooth of one blade is moved past a corresponding tooth of the other blade.

The cutting device constituting the present invention is provided with a stop member or guide in the shape of a foot which rests against the patient's body during the course of the cutting operation. It is this stop member or guide which prevents the saws from reaching and injuring the patient's skin and other tissues. In other words, it controls the depth of the cut to make absolutely certain that the cutter will attack the plaster cast and its underlying padding only, and not the patient who wears the cast. This stop member or guide is also adapted to prevent the saws and their bearing supports from burning the patient's skin. The sawing action proceeds at a high rate of speed and considerable friction and heat are thereby generated. The stop member or guide is completely separate from the saws and their bearing supports and hence the heat which the cutting operation generates is not transmitted or conducted through the stop member or guide to the patient's body. The stop member or guide performs still another function. It provides a wedging effect upon the plaster cast and its underlying padding to elevate them above the patient's skin and to bring them into engagement with the saws. This, of course, is especially true of the padding since the plaster itself may be inflexible to yield in this manner.

The present device renders it possible to engage in plaster cast cutting operations and activities which are well beyond the range and scope of action of the primitive cutting means and methods used and practiced today. For example, there are times when a plaster cast becomes unsuitable for continued application to a given patient by reason of reduced swelling in the limb which it encloses. Present methods require that the plaster cast be removed from the limb, i. e. destroyed, and that a new plaster cast be replaced thereon. The present device renders it possible to save the old cast by simply cutting a strip out of it and then fitting it to the swelling reduced limb. It is also possible by means of the present device, to increase the comfort of patients whose trunk is completely encased by means of a plaster cast. Such patients suffer intensely, especially in warm and humid weather, since there is no way at the present time of relieving or alleviating the harmful and intensely annoying and irritating conditions which are produced by perspiration and heat underneath the cast. Aside from the discomfort which is thereby caused, rashes and skin infections invariably result. The present device renders it possible, with the initial aid of a suitable drill, to cut windows into the plaster cast, without weakening it in any serious or substantial respect, for the purpose of providing adequate ventilation and also to provide access to the patient's body, for cleaning purposes, sponging it with alcohol and other important purposes.

A preferred form of this invention is shown by way of illustration in the accompanying drawing in which

Fig. 1 is a side view of the plaster cast cutter herein claimed, showing the plaster cast and its underlying padding in section.

Fig. 2 is a front view of said plaster cast cutter with its cover removed therefrom to expose its working parts.

Fig. 3 is a longitudinal section on the line 3-3 of Fig. 2.

Fig. 4 is a transverse section on the line 4-4 of Fig. 3.

Fig. 5 is a perspective view of the two saw blades which the plaster cast cutter employs.

Fig. 6 is an enlarged sectional view taken across the two saw blades when they are mounted in the cutter, showing their tapered sides.

Fig. 7 is a longitudinal section through a presser foot construction by which the plaster cast is held steady during the cutting operation.

The preferred form of the invention which is shown in the drawing includes a motor housing 10 which has an electric motor mounted therein, together with a suitable gear arrangement, either for speed reducing or speed increasing purposes, as desired or required, or simply for drive transmission purposes without either an increase or a decrease in speed. Extending forwardly from said housing is a drive shaft 11 which is connected to the gears inside the motor housing. It is this drive shaft which operates the mechanism hereinafter described. An electric cord 12 is connected to the motor in the usual manner. Also fastened to the motor housing is a handle 13 by which the cutter may be held in the hand and operated. A switch 14 which is located on the motor housing underneath the handle, controls the motor circuit. The operating mechanism of the present device is located in front of the motor housing and a cover 15 is provided to enclose said mechanism.

The heart of the operating mechanism of this device is a pair of crank wheels 20 and 21 respectively, which actuate a pair of connecting rods 22 and 23 respectively, which, in turn, are connected to, and actuate, a pair of longitudinally movable rods 24 and 25 respectively. Saw blades 30 and 31 are connected to rods 24 and 25 and when the crank wheels and connecting rods cause said rods 24 and 25 to move longitudinally of themselves in reciprocating fashion, the saw blades are thereby caused to engage in the same kind of reciprocating movement. More specifically, crank wheels 20 and 21 comprise a pair of gear wheels which are in engagement with a third gear wheel 33. Crank gear wheels 20 and 21 are mounted respectively on stud shafts 34 and 35 and gear wheel 33 is mounted on drive shaft 11 aforementioned. Hence when the motor is in operation, gear wheel 33 will cause crank gear wheels 20 and 21 to rotate on their respective stud shafts, in the same direction. Screws 37 and 38 serve as crank pins for attaching connecting rods 22 and 23 to said crank gear wheels 20 and 21 respectively. There is a 180° distance separating the location of crank pin 37 on crank gear wheel 20 from the location of crank pin 38 on crank gear wheel 21 and hence said connecting rods 22 and 23 will move in opposite directions despite the fact that the two crank gear wheels rotate in the same direction.

Longitudinally movable reciprocating rods 24 and 25 are slidably mounted in a pair of bearings 40 and 41 respectively. It will be noted in Figs. 2 and 3 that these two reciprocating rods are mounted in parallel relationship in said bearings.

Rods 43 and 44 are fastened to bearing 41 on opposite sides of the two reciprocating rods and in spaced, parallel relationship thereto. Slides 45 and 46 are fixed to reciprocating rods 24 and 25 and they are slidably mounted on said fixed rods 43 and 44. Pins 47 and 48 pivotally connect connecting rods 22 and 23 to slides 45 and 46 and since said slides are fastened to reciprocating rods 24 and 25, it is by means of said pins and said slides that the connecting rods are attached to the reciprocating rods.

It will now be noted that the two bearing members 40 and 41 are fastened by means of screws 49 to a housing 50 which may, or may not, be integral with the motor housing. The drawing shows housing 50 as a separate housing which is fastened by means of screws 51 to the motor housing, but this should be understood as being simply illustrative of the present construction. For the purposes of the present application, however, it will be assumed that housing 50 is a part of the motor housing and it is immaterial whether the two housings are integral with each other or not. Housing 50 has an upwardly projecting portion 52 and a downwardly projecting portion 53. A channel 54 is formed in the upwardly extending portion 52 and a second channel 55 is formed in the downwardly extending portion 53. These channels are adapted to accommodate the reciprocating rods 24 and 25 in their respective upward and downward movements in bearings 40 and 41. Connected to the lower end of reciprocating rod 24 is a block 58 and a similar block 59 is fastened to the lower end of reciprocating rod 25. It is to these blocks that the saw blades are attached by means of screws 60. More specifically, it will be seen that the upper ends of the two saw blades are provided, respectively, with side pieces or flanges 62 and 63 which have holes 64 and 65 formed therein. These flanges 62 and 63 are adapted to rest upon blocks 58 and 59 and it is through holes 64 and 65 that screws 60 may be inserted to affix said flanges, and hence the saws, to said blocks. As the reciprocating rods and their respective blocks engage in reciprocating upward and downward movement, so do the saw blades engage in the same reciprocating movement.

It will be seen in Fig. 5 that the two saw blades are not interchangeable and hence one may be described as the left saw blade, and the other as the right. The teeth 70 of one of said blades, that is blade 30, are provided with cutting edges which face downwardly. Teeth 71, on the other hand, of blade 31, have cutting edges which face upwardly. Hence the cutting action of saw blade 30 takes place on its downward stroke and the cutting action of blade 31 takes place on its upward stroke. It will be noted in Fig. 2 that crank pins 37 and 38 are so situated on the crank wheels, that the greatest possible leverage is brought to bear upon the saw blades during the course of their cutting strokes.

The cross sectional view of the blades which Fig. 6 constitutes, discloses the fact that the two blades abut each other on their respective facing sides. Since the teeth of said blades, at least along their said facing sides, are not offset from each other, it will be clear that the teeth of each blade will slidably abut the teeth of the other blade when the two blades are caused to reciprocate relative to each other. A cutting action will thereby be set up between the teeth of the respective blades which will cut or shear the cotton or gauze padding 80 underneath plaster cast 81. If it be assumed that the cutting edges of teeth 70 face downwardly and the cutting edges of teeth 71 face upwardly, it will be apparent that the cutting action will take place between the two blades only when blade 30 moves downwardly and blade 31 moves upwardly. If desired, cutting edges may be provided on both sides of the cutting teeth of both blades so that a cutting action will take place on the upward and downward strokes of the two blades.

It will also be seen in Fig. 6 that the non-facing sides of the two blades are tapered in opposite

directions, that is, they converge from their relatively thick teeth portions to their relatively thin back edge portions. These tapers on the two blades are provided for the same reason that saw teeth are normally offset on hand saws, that is, to cut a slightly wider groove or saw cut into the material or work than the body of the blade would require, thereby providing clearance for the body of the blade.

10 It will also be seen in Fig. 6 that the back edges 83 and 84 of blades 30 and 31 are still further tapered and that they meet virtually at a point. These tapered back edges fit into a V-shaped groove or channel formed in a guide block 85 on a post 86. This post is fastened to housing 50 immediately behind the two saw blades and its thickness corresponds approximately to the combined thicknesses of said two saw blades. At the bottom of column 86 is a bifurcated foot 87 which straddles the two blades and helps prevent them from bending or spreading apart. Block 85 performs the same function since its V-shaped channel tends to cam or wedge the two blades together and the harder the blades are pressed against the work, the more tightly will said block 85 hold the two blades together. In other words, block 85 serves as a guide or track for the two saw blades, holding them in close abutment with each other and bracing them against rearward bending or yielding when they are pushed hard against the work.

15 A second column 90 is affixed to housing 50 behind, and in spaced, parallel relation to column 86. This column 90 has a foot 91 which extends forwardly and below foot 87. At its forward end it is bent upwardly and backwardly to form a wedge or ramp 92. Foot 91 constitutes a guide or stop member which rests against the body of the patient to prevent the saw blades from injuring him. Since foot 91 and column 90 which supports it are separate and apart from column 86, block 85 and foot 87, said foot will remain relatively cool even though said blades, block, and foot 87 may become exceedingly hot during the course of the cutting operation. Wedge or ramp 92 will lift the work to the level of foot 87 to enable the blades to enter into cutting engagement with said work. See Fig. 1. This wedge or ramp will also serve as the means of spacing the plaster cast and the padding which lies below it, from the body 90 of the patient.

20 Referring now to Fig. 7 it will be noted that a spring-urged presser foot may be employed to press down upon the plaster cast to hold it steady and to reduce vibrations during the cutting operation. The presser foot construction includes a casing 15a which is adapted to be mounted upon casing or cover member 15 by means of the same screws which hold said cover or casing member to the main casing or housing or the device. Casing member 15a comprises a tubular housing 95 having ears or lugs 111 formed thereon and holes 112 formed in said ears or lugs. It is through these holes that screws 113 may be inserted in order to fasten casing member 15a to casing member 15, and both of said casing members to the main casing of the device. Housing 95 has a cylindrical hole 96 formed therein longitudinally thereof. A piston-like member 104 is slidably mounted in said cylindrical hole and it will be noted that a set screw 105 is fastened thereto and that said set screw rides in a longitudinal slot 106 formed in the wall of said tubular housing 95. This screw-in-slot construction enables the piston-like member 104 to move longitudinally

in the cylindrical hole, but it prevents rotary movement of said piston-like member in said hole. Also screw 105 serves as a stop member which limits the longitudinal stroke of the piston-like member 104 to the length of slot 106, less the diameter of said screw. Connected to the top of piston-like member 104 is a stem 107 which projects upwardly through a hole 110 in an externally threaded bushing 108. This bushing is screw threaded into tubular housing 95 and it has a knurled head 109 so that it may be adjusted in said tubular housing. A compression spring 98 is mounted in cylindrical hole 96 and upon stem 107. Its upper end bears against threaded bushing 108 and its lower end bears against piston-like member 104. This arrangement of parts tends to urge the piston-like member 104 downwardly as far as its screw 105 in slot 106 will allow it to go. The tension of the spring may be adjusted by simply turning knurled head 109 of threaded bushing 108.

A presser foot 100 is rotatably fastened to the lower end of piston-like member 104. This presser foot is a button-shaped member which is convex on its lower surface. It is this surface which makes contact with the plaster cast and holds the plaster cast firm against foot 91 above described. More specifically, it is the tension of spring 98 which holds the presser foot against the plaster cast and holds the plaster cast against ramp 92 of foot 91. Presser foot 100 has a cylindrical boss 99 projecting upwardly therefrom and into a correspondingly shaped hole formed in piston-like member 104. A screw 101, whose head lodges in a recess 102 in the bottom of the presser foot, extends through an axial hole in the presser foot and in boss 99 and into a threaded hole 103 formed in piston-like member 104. It is by this means that the presser foot is rotatably mounted in the lower end of the piston-like member 104. Although screw 101 is tight in its said threaded hole 103, it is relatively loose in presser foot 100 to enable said presser foot to swivel or rotate about it.

It will be understood from the foregoing that what is shown in the drawing and what has above been described in detail is simply one preferred form of the invention. This preferred form may be modified in many ways and other forms may be provided, all within the broad scope and coverage of the invention. For example, the drive mechanism which accommodates the two saw blades is merely illustrative of the many kinds of driving mechanisms which may be employed to cause the two blades to move alternately upwardly and downwardly, in opposite directions. The specific type of saw blade which is shown in the drawing is also purely illustrative of the many different kinds of saw blades, and even files, which may be used in connection with the present invention. Nor need the saw blades be of the reciprocating type. Circular blades driven in opposite directions would also perform well.

I claim:

1. A portable power-driven cutting machine comprising, in combination, a motor housing, an elongated guide member having a V-grooved blade support rigidly extending from said housing, a pair of reciprocable cutting blades slidably mounted side by side in the groove of said support, the cutting edges of said blades being wider than said support, the back edges of said blades being tapered to fit into the groove of said support, a guard member rigidly attached to said housing

and extending therefrom parallel to but spaced from said guide, said guard member underlying the ends of said blades opposite from said housing, and motor-driven means in said housing for oppositely reciprocating said blades.

2. A portable power-driven cutting machine comprising, in combination, a motor housing, an elongated guide member having a V-grooved blade support rigidly extending from said housing, a pair of reciprocable cutting blades slidably mounted side by side in the groove of said support, the cutting edges of said blades being wider than said support, the back edges of said blades being tapered to fit into the groove of said support, a guard member rigidly attached to said housing and extending therefrom parallel to but spaced from said guide, said guard member underlying the ends of said blades opposite from said housing, motor-driven means in said housing for oppositely reciprocating said blades, and vertically yieldable work-holding means adjacent to but disengaged from the cutting edges of said cutting blades, said work-holding means normally extending toward the ends of said blades opposite from said housing.

3. A portable power-driven cutting machine comprising, in combination, a motor housing, an elongated guide member having a V-grooved blade support rigidly extending from said housing, a pair of reciprocable cutting blades slidably mounted side by side in the groove of said support, the cutting edges of said blades being wider than said support, the back edges of said blades being tapered to fit into the groove of said support, a guard member rigidly attached to said housing and extending therefrom parallel to but spaced from said guide, said guard member underlying the ends of said blades opposite from said housing, motor-driven means in said housing for oppositely reciprocating said blades, work-holding means slidably mounted on said housing adjacent to said cutting blades, and an adjustable compression spring normally biasing said work-holding means downwardly toward the ends of said blades opposite to said housing.

4. A portable power-driven cutting machine comprising, in combination, a motor housing, an elongated guide member having a V-grooved blade support rigidly extending from said housing, a pair of reciprocable cutting blades slidably mounted side by side in the groove of said support, the cutting edges of said blades being wider than said support, the back edges of said blades being tapered to fit into the groove of said support, a guard member rigidly attached to said housing and extending therefrom parallel to but spaced from said guide, said guard member underlying the ends of said blades opposite from said housing, motor-driven means in said housing for oppositely reciprocating said blades, and a spring-loaded piston slidable along an axis parallel to said cutting blades and adapted to engage material to be cut between one end of said piston and said rigidly attached guard member.

MARTIN MERKUR.
